US0D1084654S

(12) **United States Design Patent** (10) **Patent No.:** **US D1,084,654 S**
(45) **Date of Patent:** **** Jul. 22, 2025**

(54) **AUDIO SPEAKER PROTECTION COVER**

(71) Applicant: **Shenzhen Dalianpin Technology Trading Co., Ltd.**, Shenzhen (CN)

(72) Inventor: **Aina Xu**, Shenzhen (CN)

(73) Assignee: **Shenzhen Dalianpin Technology Trading Co., Ltd.**, Shenzhen (CN)

(**) Term: **15 Years**

(21) Appl. No.: **29/962,134**

(22) Filed: **Sep. 10, 2024**

(30) **Foreign Application Priority Data**

Aug. 26, 2024 (CN) 202430541369.8

(51) **LOC (15) Cl.** **14-01**

(52) **U.S. Cl.**

USPC **D14/221**; D3/289

(58) **Field of Classification Search**

USPC D3/218, 229, 232, 238, 269, 276, 304,
D3/305, 306, 307, 308, 309, 311, 312,
D3/314, 315, 316; D6/610, 616;

D14/204, 210, 213, 221

CPC A45C 11/20; H04R 1/028

(57) **CLAIM**

The ornamental design for an audio speaker protection cover, as shown and described.

DESCRIPTION

FIG. 1 is a front perspective view of an audio speaker protection cover, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the audio speaker protection cover, which form no part of the claimed design.

1 Claim, 8 Drawing Sheets
